HYDRAULIC DIAPHRAGM

Roland Chilton, Ridgewood, N. J., assignor, by
means assignments, to Wright Aeronautical
Corporation, Paterson, N. J., a corporation of
New York

Application November 30, 1937, Serial No. 177,185

7 Claims. (Cl. 137—157)

This invention relates to flexible diaphragms or sealing means for reciprocating plungers subject to fluid pressure, the specific embodiment of the drawing being suited for a hydraulic pressure measuring cell. The chief objects of the invention are to provide a diaphragm which shall combine great flexibility for movement with complete pressure tightness and with a maximum of volumetric fluid rigidity and pressure capacity. Other objects and advantages of the invention will be obvious from, or will be pointed out in, the following description with reference to the drawing in which:

Fig. 1 is an axial section through a hydraulic cell incorporating the invention;

Fig. 2 is a fragmentary view of a partly formed diaphragm;

Fig. 3 is a cross section through a completely formed diaphragm, and

Fig. 4 is a fragmentary view illustrating the range of action of the diaphragm.

Referring first to Fig. 1, 10 designates a housing having a cover plate 12 secured by bolts 14 so as to provide a hydraulically sealed joint with an interposed composite diaphragm 16 in which the chief features of the invention reside. The housing 10 serves to guide a pressure rod 18 which engages a head 20 which rests upon the center portion of the composite diaphragm as shown. An orifice 22 is provided in the cover plate 12 whereby the lower or pressure side of the diaphragm is hydraulically connected to the means to be operated, which in this case comprises a pressure gauge (not shown) whereby the load on the rod 18 is to be measured.

The composite diaphragm 16 comprises a metallic element 24 and a sealing element 26 of flexible impervious material, preferably oil resistant rubber. Both the diaphragms consist of a flat central portion engaging the head 20 as shown and a rim portion clamped by the cover plate 12 as already described. The rim and central portions are connected by a toric or looped annular element 28 and in the case of the metal element, this annulus is slotted to comprise a plurality of ribbons integral with the central portion 24 which ribbons, by their slotted formation, are flexible to roll as indicated in Fig. 4 as the plunger 20 moves relative to the housing 10. The rubber diaphragm lies against the fluid pressure side of the slotted metal diaphragm, thereby sealing the device against leakage. The volumetric rigidity of the assembly resides in the inextensible but pliable metal ribbon elements which it will be seen are stressed

in pure tension by the hydraulic pressure under which they will naturally adopt a looped form between the plunger and housing, the radial pressures being resisted by the piston head 20 and the bore 30 of the housing 10 to which the annular loop 28 of the diaphragm is fitted.

The preferred method of manufacture of the diaphragm 24 consists in first slotting a thin metallic disc as indicated in Fig. 2 to provide clearances 32 which become narrow when the looped annulus 28 is formed in the diaphragm in suitable dies (not shown). Preferably, these dies are arranged so that when the diaphragm has been formed to the condition of Fig. 3, a rigid metallic ring 34 is secured to the outer portions, as by soldering, leaving the adjacent ribbons of the annular looped part 28 with only sufficient clearance for the slight change in relative spacing required by the rolling action indicated in Fig. 4.

The device may be obviously used for other purposes than weighing as, for example, to operate the plunger 20 by hydraulic pressure or alternately, the novel diaphragm here disclosed is suitable for use in a reciprocating pump.

It will be seen that the looped elements 28, in mid position of the diaphragm have straight elements in their respective limbs and the range of action of the device is four times the length of these straight elements. For very long strokes, it is possible that the rolling action be carried so far that a point on the metallic annulus which at the downward end of the stroke contacts the plunger head 20 will, at the upward extreme, be transferred to contact the bore 30 of the housing. For these extreme travels it is necessary that the ribbons defined by the slots be parallel sided and such slots will be virtually closed where the ribbon lies against the inner plunger. The width of slot at the outer portion of the annulus then depends upon the relative width of this element. If this be, say 10% of the inner or plunger diameter, then the maximum gap or slot width will be 10% of the width of each ribbon and the rubber diaphragm must have sufficient thickness to be capable of bridging this narrow slot under the operating hydraulic pressure. Alternately two slotted diaphragms may be assembled in staggered overlying relationship so that the ribbons of one diaphragm bridge the slots of the other, whereby the sealing diaphragm 26 will have no tendency to extrude through the slots 32.

While I have described my invention in detail in its present preferred embodiment, it will be

obvious to those skilled in the art, after understanding my invention, that various changes and modifications may be made therein without departing from the spirit or scope thereof. I aim in the appended claims to cover all such modifications and changes.

I claim as my invention:

1. In a seal for a bored housing and a cylindrical plunger, a flexible diaphragm which comprises a radially slotted thin metallic disc, defining between said slots radially extending ribbons wider than the slots, each of the several ribbons having a loop portion with straight sides normal to the disc plane, the summation of the several loops forming an annular groove in the disc by which the original diameter of the disc is reduced in virtue of said loops, and a re-enforcing ring secured around the outer ends of said ribbons, said ring and the central portion of said disc respectively engaging the housing and plunger and being adapted for axial displacement with consequent rolling shift of the loop relative to the ring and central portion, the straight sides of the loops engaging the side walls of the housing and the plunger, said radial slots being reduced from their original width by the reduction in radius of the disc.

2. In a seal for a bored housing and a cylindrical plunger, a flexible diaphragm which comprises a radially slotted thin metallic disc, defining between said slots radially extending ribbons wider than the slots, each of the several ribbons having a loop portion with straight sides normal to the disc plane, the summation of the several loops forming an annular groove in the disc by which the original diameter of the disc is reduced in virtue of said loops, a re-enforcing ring secured around the outer ends of said ribbons, said ring and the central portion of said disc respectively engaging the housing and plunger and being adapted for axial displacement with consequent rolling shift of the loop relative to the ring and central portion, the straight sides of the loops engaging the side walls of the housing and the plunger, said radial slots being reduced from their original width by the reduction in radius of the disc, and a rubber-like membrane conformed to said diaphragm and bridging said slots.

3. A diaphragm of thin flexible metal comprising an inner annulus, a plurality of laterally contiguous independently flexible ribbons integral therewith and extending radially therefrom, and

an outer annulus to which the ends of said ribbons are bonded.

4. A diaphragm of thin flexible metal comprising an inner annulus, a plurality of laterally contiguous independently flexible ribbons integral therewith and extending radially therefrom, and an outer annulus to which the ends of said ribbons are bonded, said ribbons having loops formed therein to define, in the aggregate, an annular groove between the inner and outer annuli.

5. A diaphragm of thin flexible metal, comprising inner and outer annuli, and a plurality of lateral contiguous independently flexible substantially radially extending looped ribbons of thin metal bridging said annuli, the ribbons being integral with one said annulus and being bonded to the other said annulus, the loops of the several ribbons defining in the aggregate an annular groove between said annuli.

6. A diaphragm comprising a thin initially flat resilient circular plate having narrow radial slots extending inwardly from the plate each end terminating on a circle concentric with the plate, thereby defining a plurality of radial ribbons the slots being narrower than the ribbons defined thereby, said ribbons being looped intermediate their length whereby the outer ribbon ends define a circle of less diameter than the diameter of the original plate, and an annulus of thin metal overlapping the outer ends of said ribbons and bonded thereto.

7. A re-enforcing diaphragm for an elastic membrane of rubber or the like held between an annular receptacle and a central plunger and subject to pressure on one side thereof comprising a disc of thin resilient metal underlying the membrane and slotted radially inward from the disc periphery toward, but not to, the center, whereby radial ribbons wider than the slots are defined between the slots, each ribbon having a loop formed therein whereby the diameter of the disc is substantially decreased from its original diameter, said loops defining in the aggregate an annular groove into which said membrane may deform, and a flat annulus of sheet metal overlying and bonded to the outer ends of said ribbons, the central portion of said disc and said annulus thus forming substantially rigid termini at the ends of each ribbon to which tensile stress in the ribbons is transmitted upon imposition of pressure upon the membrane and diaphragm ribbons.

ROLAND CHILTON.
